UNITED STATES PATENT OFFICE.

HENRY M. LANE, OF CINCINNATI, OHIO.

HORIZONTAL-CURVE CONSTRUCTION FOR CABLE RAILWAYS.

SPECIFICATION forming part of Letters Patent No. 371,601, dated October 18, 1887.

Application filed February 12, 1887. Serial No. 227,439. (No model.)

To all whom it may concern:

Be it known that I, HENRY M. LANE, a citizen of the United States, residing at Cincinnati, Ohio, have invented new and useful Improvements in Horizontal-Curve Constructors for Cable Railways, of which the following is a specification.

My invention relates to horizontal-curve constructions for cable railways. Its object is to produce an efficient and economical construction and arrangement of the system of horizontal pulleys and their immediate supports and connecting parts, and to facilitate the removal, replacement, and repairs of the same.

It also consists in the construction and arrangement of the slot-rails and tunnel-yokes with reference to the lateral support of the grip in passing curves, and in certain other minor features, hereinafter more fully set forth.

Mechanism embodying my invention is illustrated in the accompanying drawings, in which—

Figure 1 is a cross-section of the road-bed through the track-rails, slot-rails, and a curve-pulley, showing one of the tunnel-yokes (as constructed for curves) in elevation; Fig. 2, a detail section in the plane xx of Fig. 1, indicating the general web structure of the yoke-extension and of the covering-plates resting thereon; Fig. 3, a general plan view of the road-bed, including two consecutive yokes, and showing one of the curve-pulleys in position; and Fig. 4 and 5, details of the socket-rest for the hinged pulley-bearing arm.

Referring now to the drawings, A designates one of the cast-iron yokes used upon curves. The left-hand half of said yoke, as indicated in Fig. 1, with its slot-rail a' , its brace b , and tie-bar c , (forming a bracket supporting the left-hand track-rail R'), is identical in construction with that of the yoke described by me in former patents, and need not be further referred to here. For use upon curves, however, the yoke is cast with a projection or web, A' , extending at one side to the vertical line of the track-rail R , for which rail it forms a support. This extension is preferably cast in the form of a partial or entire web similar to that of the body of the yoke, and strengthened by a marginal flange, d , similar to that of the yoke itself, of which it is an extension.

The extension A' is carried under the track-rail R to form a bottom support, and is formed to fit the contour of the rail at the inside of the latter, the web d being enlarged at the side of the rail to admit a bolt horizontally through itself and the rail, securing the latter in position and preserving the proper gage of the track.

When the yoke is in position it occupies, with its lateral extension, a radial relation to the general curve of the track, the said extension being toward the center of said curve. The slot-rail a is in this instance arranged with its main web in a vertical plane, the corresponding jaw of the yoke being formed to secure it in such position upon a bracket or offset, a^2 , from the inner face of the yoke, constituting a bottom support. This slot-rail is secured to the yoke by bolts passing through the flanges of the yoke from the outside and screwed into tapped holes in the slot-rail to present a flush surface with said rail within the tunnel, so that in case the bolts work loose they recede from such flush surface. As thus constructed and arranged, the said slot-rail a forms a bearing-rail, against which the grip G slides, and which takes the lateral strain of the cable c in passing around curves, as indicated by the position of the grip device G in Fig. 1, and the fastening-bolts can under no circumstances form an obstruction. A ledge, a^2 , is formed upon the outside of the slot-rail a , constituting a bearing for the covers C , which abut against each other in radial lines of the curve, meeting upon the flanged upper edge, d , of the extension A' , as indicated in Fig. 2, and held laterally by their strengthening-webs w , fitting within and between contiguous partitions A' .

The yokes and extensions rest upon a concrete foundation, as indicated by the broken lines in Fig. 1, the surface of that portion of said foundation beneath the extension inclining inward to drain into the bottom of the main tunnel. Against the outer edges of the extensions A' a wall, e , of timber is laid from the concrete foundation up to the track-rail R , against the outside of which the earth is filled. There is thus formed a side extension of the main tunnel around the curve, opening into the main tunnel, and divided radially by the extension A' , constituting partition-walls. In this side tunnel, between each two yokes

and partitions, I mount a horizontal - curve pulley, D, in the following manner: The pulley D is suspended by a stud, s, from a supporting-arm, E, hung pivotally in hangers F, 5 bolted to the outside of the slot-rail *a* in the manner already described for securing the said slot-rail to the yokes. The outer end of the arm E has its bearing in a suitably-formed socket against the inside of the rail R, the 10 horizontal flange of the rail being recessed, as indicated in Fig. 3, to permit the arm to be forced downward a little to one side of its true vertical plane and "spring" under said flange sidewise. To secure the arm against lost motion and displacement, a short arm, *f*, with a cam-shaped end, is pivoted to the side of the main arm E, near its outer end, which, when said main arm is in position, is turned so as to elongate the arm and lock it in position 15 by lineal compression between its end supports. To insure a secure holding of the arm E, I cast or attach to the side of the rail R a socket-piece, *g*, formed as shown in Figs. 4 and 20 5, which has an opening corresponding with the recess of the horizontal flange of the rail R, and is offset sidewise below to admit the arm E first downward and then sidewise into a holding-socket, securing it against vertical displacement, where it is locked by the cam- 25 arm *f*, acting against the surface *g'* of the socket-piece.

The hangers F are formed as two depending arms or hooks cast with and upon a base-plate, *f'*, which rests against and is bolted to the outside of the slot-rail *a*, as indicated in Fig. 3. The arm extends between the hangers F, and is upheld upon lateral pivots *p*, extending at each side of the arm and resting in the hangers. The parts are to be so proportioned and 30 adjusted as to allow the arm E to be readily loosened by turning the locking-cam *f*, which may then be turned up and used as a handle to swing the arm E upon its pivotal bearing and elevate the pulley D out of its cavity into a 35 vertical position. The entire pulley device may be then lifted bodily out of the hangers and cavity, if desired.

In the center of the arm E is an enlargement, through which the stud *s* passes and is secured. 50 I form in this enlargement, adjacent to the central stud perforation, an oil-chamber, *h*, open above and there provided with a hinged lid, and through the bottom of said chamber drill an oil-channel to the wheel-bearing below. 55 The chamber is made large enough to contain sufficient oil to last between inspections made at proper intervals.

I claim as my invention and desire to secure by Letters Patent of the United States—

60 1. In curve constructions for cable railways, a cast tunnel-yoke having jaws between and upon which the slot-rails are secured, one of said jaws being extended laterally to and beneath the inner track-rail to constitute a gage and support therefor, and a dividing and supporting partition for contiguous horizontal-

curve pulley - casings, substantially as set forth.

2. In curve constructions for cable railways, in combination with a cast yoke having vertical jaws extending to or approximately to the roadway-surface and forming a backing and vertical support for the slot-rails placed upon and between said jaws, the inner slot-rail, so backed by the yoke and arranged to present its convex surface as a guideway for sliding contact of the grip and resist lateral strains of the cable, substantially as set forth. 70 75

3. In curve constructions for cable railways, the combination of two contiguous tunnel-yokes having lateral extensions carrying the track-rails, a curve pulley mounted horizontally between two such extensions at one side of the main tunnel, and two curved slot-rails carried between and by the jaws of the yoke, 80 85 one of which slot-rails presents its web in a vertical plane as a guide-rail for sliding contact of the cable-grip, substantially as and for the purpose set forth.

4. In a cable railway, in combination with the tunnel-yokes, a curved guide-rail for sliding contact with the cable-grip device, having a web vertical or approximately vertical seated upon and backed by the yoke-jaw and terminating in a horizontal flange constituting 90 95 the surface slot-rail, said guide and slot-rails formed as one structure, substantially as set forth.

5. In a cable railway, in combination with a cast yoke having jaws between and upon which the slot-rails are supported, and its web extended at one side to constitute a support for the inner track-rail of the curve, the inner slot-rail constituting a curved guide-rail for sliding contact of the grip terminating in a 100 105 horizontal flange constituting the slot-rail, substantially as set forth.

6. In a cable railway, the yoke A, provided at one side with bracket *c b*, supporting the outer track-rail, R', and at the other extended into a partition, A', separating curve-pulley chambers, and fitted to the side and bottom contour of the inner track-rail to preserve the gage of the track and constitute a bottom support for the inner track-rail of the curve, substantially as set forth. 110 115

7. In curve constructions for cable railways, the combination of a horizontal idler curve pulley with a carrier-arm held in pivotal bearings upon the outside of the slot-rail and extending to and locking against the track-rail, substantially as set forth. 120

8. In cable-railway curve constructions, the combination, with two contiguous yokes and the inner slot-rail, of a carrier-arm pivotally connected to said slot-rail between said yokes, and carrying a horizontal cable-pulley adapted by the pivotal bearing of its supporting-arm to be turned upward with its arm out of the roadway-surface opening, substantially as set forth. 125 130

9. The combination of the slot-rail *a*, hang-

ers F, arm E, pulley D, and track-rail R, substantially as set forth.

10. The combination of the arm E, pivotally mounted at one end upon the slot-rail a, and carrying the pulley D, with the locking-arm f and track-rail R, substantially as set forth.

11. The combination of the pivoted arm E, carrying the pulley D and provided with the locking-arm f, with the track-rail R, provided with the socket-piece g g', substantially as specified.

12. The arm E, provided with the oil-receptacle h and carrying the pulley D, substantially as and for the purpose set forth.

15 13. The combination of the yoke A, having radial extensions A', with the curved inner slot and guide-rail a, and curved inner track-

rail, R, secured to said extension against the ends thereof, respectively, constituting a curved "truss" to resist the lateral strains of 20 the cable upon the pulleys and the sliding grip, substantially as specified.

14. The combination of the yokes with radial extensions, the inner slot-rail, inner track-rail, and the covers C, abutting in radial lines 25 upon the upper edges of the extensions, substantially as set forth.

In testimony whereof I have hereunto set my hand in the presence of two subscribing witnesses.

HENRY M. LANE.
